(57) **CLAIM**

The ornamental design for a casing catcher, as shown and described.

DESCRIPTION

FIG. 1 is a perspective view of the casing catcher of my new design, showing the device attached to the barrel of a hand gun.

FIG. 2 is a rear elevational view of the casing catcher of my new design shown in FIG. 1.

FIG. 3 is a front elevational view thereof.

FIG. 4 is a top plan view thereof.

FIG. 5 is an elevational view of one side thereof.

FIG. 6 is an elevational view of the opposite side thereof; and, FIG. 7 is a plan view from the bottom thereof.

The broken line elements shown in FIG. 1, showing a hand gun, are environmental, and form no part of the invention.
